UNITED STATES PATENT OFFICE.

JACK MCKINZIE, OF LUNET, ARKANSAS.

DESIGN FOR A BUTCHER'S CLEAVER.

SPECIFICATION forming part of Design No. 31,534, dated September 19, 1899.

Application filed July 18, 1899. Serial No. 724,311. Term of patent 7 years.

To all whom it may concern:

Be it known that I, JACK MCKINZIE, a citizen of the United States, residing at Lunet, in the county of Ouachita and State of Arkansas, have invented and produced a new and original Design for Butchers' Cleavers; and I do declare the following to be a full, clear, and exact description of the same, reference being had to the accompanying specification and drawings, forming a part thereof.

Figure 1 is a plan view of a cleaver, showing my new design. Fig. 2 is a cross-sectional view taken on the line *x x*.

As shown in the drawings, the leading or material feature of my invention consists of a blade 1, having a curved edge 2, which ta-

pers back to a point 3, and at its rear end is cut back to fit in a handle 4.

My design is also provided with a hatchet-blade 5 and a perforation 6.

4 is a handle firmly secured to the blade.

Having described my invention, what I claim as new, and desire to secure by Letters Patent, is—

The design for a butcher's cleaver, as herein shown and described.

In testimony whereof I affix my signature in presence of two witnesses.

JACK MCKINZIE.
